G. J. KRAUSHAAR,

BAKER'S PEEL,

APPLICATION FILED SEPT. 8, 1913.

1,216,703.

Patented Feb. 20, 1917.

UNITED STATES PATENT OFFICE.

GEORGE J. KRAUSHAAR, OF CLEVELAND, OHIO.

BAKER'S PEEL.

1,216,703.

Specification of Letters Patent. Patented Feb. 20, 1917.

Application filed September 8, 1913. Serial No. 788,497.

To all whom it may concern:

Be it known that I, GEORGE J. KRAUSHAAR, citizen of the United States, residing at Cleveland, in the county of Cuyahoga and State of Ohio, have invented certain new and useful Improvements in Bakers' Peels, of which the following is a specification.

This invention consists in an improvement in bakers' peels, all substantially as shown and described and particularly pointed out in the claim.

In the accompanying drawings, Figure 1 is a bottom view of a peel constructed according to my invention. Fig. 2 is a longitudinal sectional elevation thereof, and Fig. 3 is a cross section on line 3—3, Fig. 1.

The improvement as thus shown comprises a metallic blade *b*, preferably of aluminum but not limited thereto nor to any particular metal though lightness is important, and designed to substitute the wooden peel in common use. Of course I am aware that others have made metallic peels of one form and another and I do not therefore lay claim to originality in the use of metal for this purpose except that mine is made of aluminum and therefore light and otherwise desirable, but I am not aware that any one has ever before made or known of a peel having the structural peculiarities of my invention. It is also to be noted that notwithstanding ventures heretofore made in metallic peels it remains true that the old-fashioned wooden peel is the only one in common use and it has been holding the trade as if no other kind had ever been known or used. But a wooden peel has a large number of weaknesses or objections and, notably, its liability to split and also to burn. In fact it requires the very best of wood and specially skilled workmanship to make a wooden peel which will hold its shape through all conditions of temperature and last a reasonable length of time, and this makes such peels very expensive at first cost in addition to being short lived at the best.

The present invention is, therefore, designed to provide a thoroughly practical construction of all metal which is light in point of weight and which will last for an indefinite period because it is strong and rigid and can even be left in the oven during baking and not be injured by the heat.

To these ends the peel shown is cast from

aluminum with a so-called body or blade 55 having a flat smooth top surface its entire length and width and a series of longitudinal tapered-ribs 3 on its bottom lengthwise and terminating at the rear edge of the front approximately wedge-shaped portion 4. The taper of the said ribs is from the rear to the front and the two central ribs terminate at the rear in a special reinforcement 5 immediately at the front of the socket portion 6 for the handle 7 thereby 60 constituting a spider like formation at the rear and bottom of the blade. The said ribs serve to strengthen the blade between its ends and to give a practically rigid effect notwithstanding the comparative lightness of the article as a whole, and hence the 65 convenience and ease in handling, which are material considerations in an article of this kind.

Ease and convenience in the manipulation 75 of the peel in the oven are further enhanced by means of two roller balls or casters of ball shape indicated by 8 and supported in suitable sockets cast in the body and rear of the blade in a balancing relation as to the 80 sides thereof and so disposed and arranged that the weight upon the peel will be carried by the said balls. A suitable cage or cap 10 is employed to confine the ball in said socket and has a flange about its edge 85 through which it is riveted or otherwise secured to the body about the socket therein. By these means the peel can be loaded and run on said rollers to the rear portion of the oven with comparative ease, and the said 90 rollers are equally advantageous in removing the baking from the oven. A smooth even top surface is desirable on several accounts, as, for example, in the handling of rye bread which is baked directly upon the 95 bottom of the oven. The unbaked loaves are therefore placed on the peel and run in thereon and dipped off onto the oven floor by a quick back action upon the peel.

What I claim is:

As a new article of manufacture, a baker's peel having a blade cast in a single piece of metal and provided with a flat top from end to end and a spider formation at its rear and bottom constructed to affix a handle thereto and having a series of longitudinally disposed ribs at intervals between its sides tapered from the rear toward its front

and the front portion of the peel flat on both sides in advance of said ribs, and said blade having sockets at its rear and sides and caster balls in said sockets projecting beneath said ribs and adapted to provide a universal movement for said blade over the surface of the oven.

Copies of this patent may be obtained for five cents each, by addressing the "Commissioner of Patents, Washington, D. C."

In testimony whereof I affix my signature in presence of two witnesses.

GEORGE J. KRAUSHAAR.
